SAFETY HAT

Edward W. Bullard, San Francisco, Calif., assignor to E. D. Bullard Company, San Francisco, Calif., a corporation of California.

Application February 12, 1936, Serial No. 63,619

7 Claims. (Cl. 2—3)

My invention relates to safety hats; and particularly to a hat for use as protection against head injuries by falling objects or other similar hazards.

5 It is among the objects of my invention to provide a safety hat of light, yet rugged construction, which may be worn with comfort, and which will effectively protect the head of the wearer.

10 Another object of my invention is to provide a structure which may be readily adapted to fit heads of various size and shape.

Another object is to provide a safety hat structure which will facilitate the placing and adjustment of a lining and head band in the crown of the hat.

Another object is to provide a safety hat structure arranged to obtain effective ventilation of the hat crown.

Another object of my invention is to provide a safety hat embodying features of structure and arrangement obtaining simplicity and economy in manufacture, and comfort and efficiency in use.

The invention possesses other objects and features of advantage, some of which, with the foregoing, will be set forth in the following description of my invention. It is to be understood that I do not limit myself to this disclosure of species of my invention, as I may adopt variant embodiments thereof within the scope of the claims.

Referring to the drawings:

Figure 1 is a side elevation of a safety hat embodying my invention, parts being broken away to show features of the construction.

35. Figure 2 is a view of the bottom and interior of the hat shown in Figure 1, and illustrating the manner in which the lining and head band are mounted.

Figure 3 is a side elevation, partly in vertical mid section, of another hat structure embodying my invention.

Figure 4 is a broken sectional detail of the lining and head band mounting means as embodied in the structure illustrated in Figures 1 and 2.

Figure 5 is a broken sectional detail of the lining and band mounting means as embodied in the structure illustrated in Figure 3.

Figure 6 is a broken vertical sectional detail 50 of the top ventilation means as embodied in the hat structure of Figures 1 and 2.

Figure 7 is a similar detail of the top ventilating means of the hat structure of Figure 3.

In terms of broad inclusion, the safety hat of my invention comprises a crown, preferably

formed of compacted fibrous sheet material, shaped to provide a rigid dome-like protective covering for the head. Preferably, the crown comprises a pair of rigid arched crown forming sheets crossing each other at the top of the crown, and having the end portions widened and overlapping to form the front, back, and sides of the crown.

A lining and head band are detachably mounted within the crown by means of a plurality of suspension straps secured within the lower portion of the crown, the straps preferably being inserted thru openings in the lining, and being provided with suitable fastening means engaging the head band, whereby both the lining and the head band are detachably secured in operative relationship to the crown. 10 15

My invention also contemplates the provision of ventilating means for the hat crown including a ventilating opening extending entirely around the crown between the head band and the crown, and also an opening in the top of the crown shielded by a boss having openings in its sides to permit the circulation of air and at the same time prevent the entrance of liquid or solid substances into the crown when the hat is being worn.

In terms of greater detail, the safety hat of my invention comprises a rigid dome-shaped crown, 1, preferably formed from compacted fibrous sheet material of a weight suitable for protecting the head of a wearer from injury by falling objects, or other heavy blows. Sheet material of that kind having a thickness of about $\frac{1}{8}$ to $\frac{1}{2}$ of an inch is light and readily formable, and at the same time affords a high degree of rigidity and resistance to crushing or piercing when formed into a hat crown. The use of compacted fibrous material is also desirable because it is water-proof, and a non-conductor of electricity.

In the embodiment illustrated in Figures 1 and 2, the crown 1 is formed from a pair of arch shape crown pieces 2 and 3 crossing at substantially right angles at the top of the crown. 45 The ends of the sheets 2 and 3 are widened to overlap along their adjacent edges, and form the front, back and sides of the crown.

The sheets 2 and 3 are cut from suitable stock, and are pressed into the desired form. The lower edges of the sheets 2 and 3 are sewed, or otherwise secured to a ring 4 for holding the crown sheets in crown-forming relation. 50

The ring 4 is preferably formed of material similar to that of the crown sheets 2 and 3, and

extends entirely around the interior of the formed crown at the lower edge thereof. The ring 4 is preferably provided with a vizor or brim 5 formed integrally therewith. Slits 6 may be made at intervals along the upper edge of the ring 4 to facilitate the shaping of the ring and vizor.

The sheets 2 and 3 are preferably secured only at their lower edges, the intervening arched portions being left free so that each may yield under pressure or under a blow independently of the other. This structure obtains increased resilience; and avoids weakening of the crown due to the application of securing means therethrough.

15 The underlying crown sheet 2 is preferably provided with a ventilating opening 7 at approximately the center of the top of the crown. The overlying sheet 3 is provided with a boss 8 formed therein to span the opening 7. Ventilating openings 9 are formed in the sides of the boss 8 to permit the circulation of air thru the crown of the hat and at the same time prevent the entrance of water or other liquid or solid material into the hat through the opening 7 when it is being worn.

25 The crown 1 is made of a size substantially greater than the ordinary head size; and is fitted to the head of a wearer by means of a head band 11. The head band 11 is mounted within the crown by means of a plurality of suspension straps 12 secured within the lower portion of the crown, the head band being connected to the strap by means of snap fasteners 13 or other suitable securing means.

35 The straps 12 may be made of leather, or other suitable material, having the required strength and flexibility. In the embodiment illustrated in Figures 1, 2, and 4 of the drawings, the straps 12 are secured at their upper ends to the upper ends 40 of tongues 14 extending upwardly from the ring 4 within the lower edge of the crown. The straps 12 may be secured to the tongues 14, or other supporting means, by any suitable securing means, as for example by rivets 16.

45 The head band 11 is preferably mounted with its lower edge in substantially the same plane with the lower edge of the crown 1. The head band 11 may be formed from any suitable material, preferably sufficiently firm to be self supporting, yet sufficiently yieldable to conform to the shape of the head. Fabric impregnated and coated with a phenolic condensation product and subjected to heat and pressure to produce a smooth glazed finish has been found to be highly 55 satisfactory for this purpose. Such material is light, yet strong and durable; and possesses waterprooing properties such that it is not injured by perspiration or exposure to moisture. Other sheet material possessing similar properties, as

60 for example compacted fiber, may be substituted if desired. Head bands 11 are made to fit various head sizes; and it is only necessary to select a head band of the desired size to fit the crown to any head. The straps 12 support the head band 11 in spaced relation to the inner surface of the crown so that a relatively wide ventilating passage extending entirely around the lower edge of the crown is formed between the crown and head band.

70 The straps 12 also serve as a means for securing the lower end of lining strips 19 arranged to extend over the top of the head of a wearer to limit the extent to which the hat may be moved downwardly onto the head, and to distribute the 75 force of a blow received upon the crown. The

strips 19 are made of a strong flexible material, such as leather, and are preferably secured to the straps 12 by passing the straps thru openings 21 formed in the lower ends of the straps. The strips 19 converge toward the top of the crown, 5 and are connected by a cord 22, or other suitable connecting means, by which the ends of the strips are adjustably connected to each other. The strips 19 adapt themselves to the shape of the head of a wearer; and by taking up or letting out 10 the cord 22, the lining strips may be adjusted to suit the requirements of the individual user.

In the embodiments disclosed in Figures 3, 5, and 7 of the drawings, the crown is formed from a single piece of compacted fibrous sheet material 15 shaped to form a dome-shaped crown and secured at its lower edge to a ring 26 forming the lower portion of the crown. In this structure, the suspension straps 12 may be secured at their upper end between the crown sheet 24 and the 20 ring 26 by the stitching 27 by which the ring is sewed to the crown sheet 24. The lining strips 19 and head band 11 are secured to the straps 12 in the manner above explained in connection with Figures 1, 2 and 4.

25 In this case, as in the embodiment previously described, ventilation thru the top of the crown is effected by means of a ventilating opening 28 formed in the top of the crown sheet 24. Here, however, the boss 29 overlying the ventilating 30 opening 28 is a separate piece of sheet material secured to the outer surface of the crown sheet. The boss 29 is preferably formed with points 30 thru which securing means, as for example stitches 31, are applied. The portion of the boss 35 29 between the points 30 is raised away from the upper surface of the crown to provide ventilating openings 32 therebetween.

The lining strips 19 and head band 11 are assembled upon the crown 1 by first inserting the 40 straps 12 thru the openings 21 of the lining strips, and thereafter securing the head band to the downwardly extending ends of the strap 12 by means of the fasteners 13. By a proper selection of a head band 11 of desired size, the hat can be 45 fitted to any individual. A number of headbands may be kept on hand, and may be interchangeably used to fit the hat to a variety of head sizes.

The lining strips 19 insure that the crown 1 will 50 be held in spaced relation to the top of a wearer's head. In event a falling object should strike the top of the hat while it is being worn, the force of the blow is taken up by the lining strips 19 and distributed over the head of the wearer in such a 55 way as to avoid severe injury.

I claim:

1. A safety hat comprising a pair of resilient arch shaped crown sheets crossing at the top of the crown and having end portions forming the 60 front, back and sides of the crown, and a band secured to the lower edges of the crown sheets for securing the same in independently yieldable crown forming relation.

2. A safety hat comprising an arched crown 65 sheet of compacted fibrous sheet material and having a narrow center forming a top and widened end portions forming the sides of a crown, a second arched crown sheet of compacted fibrous sheet material crossing the narrow portion of 70 the first sheet at the top of the crown and having widened end portions forming the front and back of the crown, the arched crown sheets being yieldable in the direction of their respective lengths and transversely with respect to the length of the 75

- other sheet, and means for securing the sheets in crown forming relation.
3. A safety hat comprising an arched crown sheet of compacted fibrous sheet material and having widened end portions forming the sides of a crown, a second arched crown sheet of compacted fibrous sheet material crossing the first sheet and having widened end portions forming the front and back of the crown the widened ends 10 of each sheet spanning gaps between the end portions of the other sheet, and a band secured to the lower edges of the end portions for securing the sheets in yieldable crown forming relation.
- 15 4. A safety hat comprising a rigid crown, a lining, a head band, and a plurality of flexible suspension straps fixedly secured at their upper ends within the lower portion of the crown and detachably engaging the lining and head band for 20 securing the same within the crown.
5. A safety hat comprising a rigid crown, a plurality of flexible suspension straps fixedly secured at their upper ends within the lower portion of the crown, a lining having openings through

which the straps may extend for detachably securing the lining within the crown, and a head band detachably secured upon the lower ends of the straps.

6. A safety hat comprising a crown, a ring secured to the lower edge of the crown, tabs integral with and projecting upwardly from the ring within the crown, suspension straps secured at their upper ends to the tabs, a lining detachably engaged by the straps, and a head band secured 10 to the lower ends of the straps.

7. A safety hat comprising an arched crown sheet of rigid sheet material, a second arched crown sheet of rigid material crossing the first sheet at the top of the crown at substantially right 15 angles, the sheets having end portions widened and overlapping to form the front, back, and sides of the crown, a band securing the lower edges of the crown sheets in crown forming relation, a plurality of straps secured within the 20 lower portion of the crown, lining strips detachably engaging the straps, and a head band detachably secured to the lower ends of the straps.

EDWARD W. BULLARD.
